UNITED STATES PATENT OFFICE.

EBEN SEAVER, OF BOSTON, MASSACHUSETTS.

FIRE-BRICK.

Specification of Letters Patent No. 28,692, dated June 12, 1860.

To all whom it may concern:

Be it known that I, EBEN SEAVER, of Boston, in the county of Suffolk and State of Massachusetts, have invented an Improved

5 Manufacture of Fire-Brick for Lining for Stoves or Furnaces, and do hereby declare the same to be fully described and represented in the following specification and the accompanying drawings, of which—
10 Figure 1, is a front elevation; Fig. 2, a rear elevation; Fig. 3, a top view; Fig. 4, a bottom view; Fig. 5, an end view and Fig. 6, a horizontal section of it.

The said fire brick is constructed with 15 main and lateral air conduits or passages. It also has a curved form by which it may fit closely to the inner surface of a metallic firepot when used therein.

In the drawings, *a*, and *b*, are the main 20 conduits, one of which is vertical and the other horizontal. They open into each other, each consisting of a groove or channel. From the longer or horizontal channel, lateral holes or passages *c*, *c*, *c*, are made 25 transversely through the brick and in radial directions. The outer surface of the brick is either cylindrical or conical, or made so as to fit the inner surface of the fire pot. When used the brick is intended to rest in a 30 course of fire brick lining and to have its main channel, *a*, or *b*, to communicate with one or more air conduits leading through the side of the fire pot and so that air may freely pass into the horizontal conduit and 35 from thence through the holes, *c*, *c*, *c*, in numerous streams all of which shall converge toward the vertical axis of the fire pot

or furnace. In this way, air will be discharged either into the fuel when in combustion or into the flame thereof.

40 The air passages so formed in the brick not only operate as described, but also to enable the brick to better resist the destructive effects of the fuel. As the internal surface of the brick is about parallel to its 45 outer surface, the peculiar construction of the brick is made to contribute to its strength or ability to resist the effects of heat and shocks or blows.

Each main and lateral conduit by the 50 opposite surfaces of the brick being made parallel is situated in a concavo convex rib (as shown in the drawings) which projecting from the concave or inner face of the brick not only materially adds to its 55 strength, but is useful in protecting the rest of the lining more or less from contact with the red hot coal when the lining may be in use.

I do not claim arranging air passages in a 60 stove lining as described in the specification of the United States Patent No. 17283. In my fire brick sectional lining, the air discharging holes are led out of one long groove into which a vertical groove leads. 65

I claim—

My improved fire brick lining as made with ribs and air channels or ducts combined or arranged relatively to each other substantially as specified.

EBEN SEAVER.
